UNITED STATES PATENT OFFICE.

PATRICK J. MADDEN, OF CHICAGO, ILLINOIS.

PLUMBING-FIXTURE.

1,022,147.

Specification of Letters Patent.

Patented Apr. 2, 1912.

Application filed July 27, 1909. Serial No. 509,912.

To all whom it may concern:

Be it known that I, PATRICK J. MADDEN, a citizen of the United States, residing at Chicago, in the county of Cook and State 5 of Illinois, have invented certain new and useful Improvements in Plumbing-Fixtures, of which the following is a specification.

The present invention relates to the means for supporting the bowl of a urinal, or the 10 bowl of a lavatory, a drinking fountain or, in short, any other plumbing fixture which is not so wide as to require supporting from more than a single point, and which has a single outlet opening adapted to be 15 coupled with a single outlet pipe.

The invention is especially well adapted for urinals and I have therefore selected this adaptation of it for the purposes of this application but with the understanding that 20 I reserve to myself the exclusive right to use it on any fixture for which it is adapted.

It is well known to those skilled in the art, that bowls made of earthenware are frequently untrue, either by reason of imperfections in the molding, or by reason of their being distorted in handling while they are still soft, or by reason of their warping while being baked, and it is also known that the wall brackets for supporting them are 30 not always secured to the wall in exactly proper vertical alinement with either the communicating ends or the horizontal portions of the inlet and outlet pipe (either or both) or with the wall-openings through 35 which said pipes pass. One or more of these imperfections may make it necessary to throw the bottom of the bowl to one side or the other in order to bring its outlet opening into register with the open com-

40 municating end of the outlet pipe. If the supporting wall bracket has a straight, horizontal seat and the bowl a downwardly presented shoulder having a flat surface intended to bear thereon, this sidewise movement of the bowl will lift one end of its bearing surface of the shoulder out of contact with the seat on the bracket, and leave it in contact therewith only at the other end, especially if the bearing surfaces extend a 45 considerable distance in both directions from the vertical central line of the fixture, with the result that the overhanging lip on the shoulder of the bowl which extends downward behind the upwardly inclined 50 seat on the bracket, for preventing the forward movement of the bowl, is frequently

broken off or the bowl cracked by the unequal strain.

The object of the present invention is to provide supporting means of such construction that the lower part of the bowl may be moved sidewise, swinging about the bracket as a pivot, a distance necessary to accomplish the desired result, while maintaining an equal firm bearing on the bracket seat 65 from end to end.

To this end the invention consists in the features of novelty that are hereinafter described with reference to the accompanying drawing, which is made a part of this specification, and in which:

Figure 1 is a view partly in elevation and partly in a vertical central section of a urinal having supporting means embodying the invention. Fig. 2 is a rear elevation thereof. 75 Fig. 3 is an elevation of the supporting wall bracket. Fig. 4 is an elevation of the elastic packing which is interposed between the bracket and bowl.

A represents the bowl having inlet and 80 outlet openings a and a' located at its top and bottom, respectively.

B and B' are the inlet and outlet pipes which register with the open ends of the inlet and outlet openings, respectively, and 85 have portions which proceed laterally from the back of the bowl and through openings b and b', respectively, formed through the supporting wall or slab C. The vertical back of the bowl is countersunk, being surrounded by a marginal rib or flange D, which bears against the vertical face of the wall, and within the countersink which results from this rib or flange, and near its top has a downwardly presented shoulder 90 in the form of an overhanging lip A' formed on an arc of a circle, the inner face of the lip being sloped or inclined downward and rearward toward the wall, providing a bearing surface adapted to engage a complementary upwardly and forwardly inclined circular seat e on a bracket E secured to the wall or slab C, a packing F of soft rubber being interposed between them. The packing is molded so as to fit snugly over 100 the seat on the bracket. That is to say considered longitudinally it follows the arc described by the seat e while in transverse section it is substantially U-shape. It is manifest that with supporting means of this construction, if, when the bowl is first seated upon the bracket, its open end of the outlet

opening does not register with the outlet pipe, the bowl may be shifted upon its seat on the bracket until they do register, without disturbing the firm and continuous bearing 5 of the shoulder of the bowl upon said seat. Furthermore, the bracket and shoulder are both short and disposed equally on opposite sides of the vertical center of the fixture, so that they engage each other firmly 10 throughout their entire length.

The invention is in no wise concerned with the locations of the inlet and outlet openings or with the means for forming tight joints between them and the bowl.

15 The subject matter of the present application was shown, described and claimed, substantially, in a prior application which was filed by me December 21, 1907, under Serial No. 407,603.

20 What I claim as new and desire to secure by Letters Patent is—

1. In a plumbing fixture, the combination 25 of a bowl having an outlet opening and having at its back, above said outlet opening, a single shoulder having a bearing surface formed on an arc of a circle lying in a plane

substantially parallel with the general plane of the back of the bowl, a single bracket having a single upwardly presented seat for said shoulder formed on an arc complementary to the bearing surface of said shoulder, whereby the bowl may be adjusted about the axis of said arc, and a support to which a bracket is fixedly secured. 30

2. In a plumbing fixture the combination 35 of an adjustable bowl having at its bottom a centrally located discharge opening and having at its back, above said discharge opening, a single downwardly presented shoulder having a curved bearing surface lying in a plane parallel with the general plane of the back of the bowl, and a single bracket having a single upwardly presented curved bearing surface complementary to that of the shoulder, said shoulder, bracket 40 and outlet being located on the central vertical line of the bowl. 45
